UNITED STATES PATENT OFFICE.

GAY HENDRICKS, OF BEARDSTOWN, TEXAS.

NAIL-BOX.

SPECIFICATION forming part of Letters Patent No. 398,724, dated February 26, 1889.

Application filed November 15, 1888. Serial No. 290,886. (No model.)

To all whom it may concern:

Be it known that I, GAY HENDRICKS, a citizen of the United States, residing at Beardstown, in the county of Lamar and State of 5 Texas, have invented certain new and useful Improvements in Nail-Boxes; and I do declare the following to be a full, clear, and exact description of the invention, such as will enable others skilled in the art to which it appertains 10 to make and use the same, reference being had to the accompanying drawings, and to the letters and figures of reference marked thereon, which form a part of this specification.

This invention relates to counters, and has 15 for its object to provide bins for holding commodities, particularly hardware—such as nails, bolts, &c.—that can be conveniently handled and pushed under the counter out of the way, and which can be readily withdrawn 20 to permit free access being had for replenishing them or removing their contents.

The improvement consists of the novel construction of the bin and the supports for the same, whereby the bin is permitted to tilt and 25 is limited in its movement by the tilting sections of the supports, which will be hereinafter more fully described and claimed, and which is shown in the annexed drawings, in which—

30 Figure 1 is a front view of a counter embodying my invention; Fig. 2, a section on the line xx of Fig. 1, looking to the left; and Fig. 3, a view similar to Fig. 2, showing the bin drawn forward and tilted.

35 The counter is of ordinary construction, comprising the leg-section A, the top B, the front C, and the back D. The bin E is held between two of the leg-sections on the supports F F, each being composed of two sections, F' and F². The section F² is fixed and extends in a horizontal plane, and has its front end, f, beveled outward, as shown. The section F' is pivoted at its inner end, which end f' is beveled rearward to correspond with 40 the beveled end f. The pivot f' is near the bottom of the section, and is placed at some distance from said inner end, so that when the said section is tilted the said end f' will project above the top of the support F² and 45 form a stop, which limits the forward motion of the bin, and which is engaged by the bin

when the latter is pushed in to return the said section to its normal position. The cross-bar G limits the downward movement of the sections F' and serves for a rest for the bin. 55 The bin has rollers H, which are grooved in their periphery and which run on rails h on the supports F, the rails being shaped on their upper surface to fit the groove or other form of the rollers H. The bottom of the bin inclines from each end, meeting on a line near its rear end, to have the greatest capacity of the bin near its rear end, so that the bulk of the weight will rest on the fixed sections F² of the supports. The lower edges of the sides of 60 the bin incline from each end to correspond with the bottom.

The operation of the bin is as follows: When in a normal position, as shown in Figs. 1 and 2, the bin is supported in a nearly-horizontal position, its rear rollers resting on the sections F² and its front rollers resting on the inner ends, f', of the pivoted sections F' in the rear of their pivotal supports f'. When the bin is drawn forward, the weight being 70 shifted from the inner ends of the pivoted sections onto their front ends causes the said pivoted sections to tilt, carrying with them the bin. The inner ends, f', being thrown up above the top of the sections F², form stops 75 which engage with the rear rollers of the bin and limit its forward movement. When the bin is pushed back, the front rollers thereof, engaging with the said ends f', return the pivoted sections to their normal position. 80

Having thus described my invention, what I claim, and desire to secure by Letters Patent, is—

1. The combination, with the counter and the support for the nail-box, composed of a fixed and a pivoted guide-rail, of the bin mounted on the said support and limited in its forward movement by engaging with a portion of the said pivoted guide-rail, substantially as described. 90

2. The combination, with the counter and the nail-box support composed of a fixed and a pivoted guide-rail, of the bin mounted on the said support and having its bottom inclined downwardly from each end and meeting on a line near its rear end, substantially 100 as and for the purpose described.

3. The combination, with the counter and the nail-box support composed of a fixed guide-rail having a downwardly-beveled end, f , and a pivoted guide having an upwardly-projecting end, f' , of the bin adapted to rest on the fixed guide and on the end f' of the pivoted guide, said end f' forming a stop to limit the forward movement of the bin when the latter is tilted, substantially as described.
4. The combination, with the counter having the leg-sections A, the back D, and the cross-bar G, and the supports for the nail-box, composed of the fixed sections F^2 , having the

inclined ends f , and the pivoted sections having the inclined ends f' , which constitute 15 guide-rails, of the bin having its bottom inclined downwardly from each end, substantially as shown, and having side rollers, for the purpose described.

In testimony whereof I affix my signature in 20 presence of two witnesses.

GAY HENDRICKS.
